United States Patent Office.

CHARLES W. RHOADS, OF INDIANAPOLIS, INDIANA, ASSIGNOR TO HIMSELF, S. C. AND E. O. FRINK, AND H. A. MOORE.

Letters Patent No. 63,562, dated April 2, 1867.

IMPROVEMENT IN GATE LATCHES.

The Schedule referred to in these Letters Patent and making part of the same.

TO ALL WHOM IT MAY CONCERN:

Be it known that I, CHARLES W. RHOADE, of the city of Indianapolis, county of Marion, and State of Indiana, have invented a new and useful Latch for Fastening Gates, &c.; and I do hereby declare that the following is a full and exact description thereof, reference being had to the accompanying drawings, and the figures and letters of reference marked thereon.

The nature of the invention consists in the peculiar construction and operation of the said latch. The said latch is to be made of iron, brass, or any other suitable metal.

To enable others skilled in the art to make and use my invention, I proceed to describe its construction and operation, as follows:

The latch consists, first, of the latch-plate, represented by letter A of

Figure 1 of said drawings, which said plate is provided with a latch, D, a catch, B, a stop, J, at the bottom of slot H, so as to keep the sliding edge of the latch D as represented by letter E in a proper position to be raised and fall over the catch B, as the gate closes, where it will be firmly held, all of which is represented by No. 1 of said drawings.

Figure 2 represents the latch-plate A with a slot, H, to raise the latch D; also, slots G G, to receive the pivots F of said latch D; also, slots I I, for fastening the whole as a latch with screws to the gate, so that it can be raised or lowered to suit the settling or raising of said gate.

Figure 3 of said drawings represents the latch D with the sliding edge E and pivots F.

Figure 4 represents the catch B with the guards C C to keep the clothes off from the catch B, as people pass in and out of said gate.

What I claim as my invention, and desire to secure by Letters Patent, is—

The combination of the several devices made, constructed, and arranged substantially as and for the purpose herein set forth.

C. W. RHOADS.
